UNITED STATES PATENT OFFICE.

RUSSELL J. ANDREWS, OF DENVER, COLORADO.

AUTOMATIC SIPHON.

Application filed May 7, 1921. Serial No. 467,536.

To all whom it may concern:

Be it known that I, RUSSELL J. ANDREWS, a citizen of the United States, residing at Denver, in the county of Denver and State 5 of Colorado, have invented certain new and useful Improvements in Automatic Siphons, of which the following is a specification.

This invention relates to improvements in 10 automatic siphons for intermittent discharge of continuously flowing liquids.

The primary object of the invention is the provision of an automatic siphon of the above described character, which may be 15 specifically used in photographic work, for automatically discharging polluted and impure film wash, and in the ordinary flush tank for the intermittent discharge of liquids.

20 A further object of the invention is the provision of an automatic siphon of the above described character, which includes siphonic operated vacuum means for controlling intermittent discharge of a liquid from 25 a container.

Other objects and advantages will be apparent during the course of the following detailed description.

In the accompanying drawings, forming 30 a part of this specification, and in which similar reference characters designate corresponding parts throughout the several views,

Figure 1 is a perspective view of the improved automatic siphon.

35 Figure 2 is a cross sectional view of the automatic siphon showing details of construction, and its adjustable application to a tank structure.

In the drawings, wherein for the purpose 40 of illustration is shown a preferred embodiment of my invention, the letter A designates a tank of any approved type, such as a photographic bath tank, flush tank or the like, and which is adapted to contain 45 a liquid, continuously flowing.

The improved automatic siphon B includes the discharge pipe C which is adjustably mounted upon the floor of the tank A as by means D. Valve means E is provided 50 for regulating exit of liquid through the outlet pipe C, said valve means E being controlled through a vacuum pipe F, by a vacuum created by siphon G, which is in reality an auxiliary siphon, and which will 55 be more specifically mentioned hereinafter.

The tank A may be of any approved type,

including the floor 10 and to which floor the discharge pipe C is mounted by means of the adjustable clamp D engaging the screw threads 11 thereon. The adjusting 60 clamp D is of ordinary construction, and includes a pair of clamping nuts 13 adapted for engaging upon washers 14; a nut 13 and washer 14 being positioned upon either side of the floor 10. The automatically operated 65 siphon includes a pipe stem 15, which is integral with the discharge pipe C and the axis of which extends at right angles to the axis of said discharge pipe. A short length of pipe 16 of substantially the same dimension as the discharge pipe C and stem 15 is provided as an integral part of the stem 15, which stem 15 is centrally connected thereto. The portion of pipe 16 is in fact the inlet 70 for water adapted to be discharged from the automatic siphon, and the lower portion 17 of the same forms together with the stem 15 and discharge pipe C, the main siphon, and specific mention of which will subsequently be made. The portion 17 terminates short of 75 the bottom 10 of the tank A, and is open as at 18, to provide an inlet for liquid. A portion 19 of the pipe 16 extends upwardly from the stem 15, the bore of which is adapted to receive the valve means E. 85

The valve E is a hollow cylindrical piston, the same being disposed within the bore of the pipe 16 and freely reciprocable therein. Any type of valve E may be substituted in place of the hollow cylinder E, it being 90 merely a requisite of this valve that the same be as light in weight as possible. A screw 20 is adjustably positioned in the lower portion 17 of the pipe 16 and projects into the bore of said pipe 16, receiving the lower end 95 of the valve E, to support the same in place, whereby the entrance bore of the stem 15 may be closed, and any liability of liquid escaping into the main siphon prevented. A cap 21 is detachably mounted upon the 100 screw threads 22 of the upper end of the pipe portion 19, the same being centrally provided with a bore 23, and adapted to receive the vacuum tube F, in a detachable manner, as by means of the leak proof 105 clamping structure 24.

The auxiliary vacuum creating siphon G is preferably provided for disposition upon the outlet pipe C. Said auxiliary siphon G comprises a T-shaped casting 25, the bore 110 24^a of which is in longitudinal alignment with the bore of the discharge pipe C and

- having the lower end 26 projecting inwardly below the top of the bore of the stem 15. It is preferred that the T 25 be welded or otherwise secured in position, and in such position that the pipe projection 27 is angularly positioned to be free of any interference with the pipe 16. The lower end 26 of the auxiliary body 25 is internally screw threaded at 27^a to receive a short length of pipe 28, this pipe 28 being of sufficient length to have its outlet on the same horizontal level as the inlet of pipe 16, and in fact said pipe 28 may be constructed to extend below the inlet of said pipe. The shank or extension 27 is preferably at right angles to the longitudinal run of the body 25 of the auxiliary siphon G and is adapted to receive a length of tube 30 of approximately the same internal diameter as the pipe extension 28. This tube 30 is detachably connected to the projections 27 by means of a nut or clamping structure 31, in such manner as to make the same detachable and leak proof.
- 25 The upwardly extending end 32 in longitudinal alignment with the lower portion 24^a is externally screw threaded, and provided with an inwardly tapering face adapted to receive a plug 33 which receives an end of the vacuum tube F, the lower end of said vacuum tube F lying flush with the bottom of said plug 33. A clamping nut 34 is provided for detachably mounting an end of the tube F on the extension 32 and is positioned to engage the screw threads thereon.
- 40 The improved automatic siphon can, of course, be used for many purposes, and therefore the proportionate sizes of the various pipes can be regulated to suit the needs of a particular use. However, it is necessary that the auxiliary siphon tube 30 be of less internal diameter than the diameter of the supply pipe (not shown) which furnishes water to the tank A. This structure is provided, in order that the water may flow into the tank A in much greater quantities than the same can be discharged through the auxiliary siphon tube 30. It is 45 likewise preferred that the auxiliary tube 30 be much less in effective discharge capacity than the discharge capacity of the main siphon as formed by the respective pipe portions 17, 15, and C.
- 50 In operation, the water is supplied to the tank A, the level in said tank rising until the same is slightly above the upper surface of the projection 27 forming a portion of the auxiliary valve E, and at which time atmospheric pressure will force the water into the tube 30 to be discharged through the extension 28 and out through the main discharge pipe C. In this manner, the auxiliary siphon will function, and as the water 55 flows through the same to be discharged, suction will be created upwardly through the portion 32 of the vacuum creating siphon means G, which suction will be transmitted through the pipe F into the bore of the upper portion of the pipe 16. This 60 vacuum suction will act upon the top of the valve or piston E and when the suction becomes sufficiently perfect, as the air is exhausted from the portion 19, the piston or valve E will be raised in the bore of the portion 19 until the same is lifted free of the bore of the stem 15, and the main siphon immediately starts to function. Since as before mentioned the flow of water into the tank A is much greater than the discharge through the auxiliary siphon G, said liquid will not be lessened in height due to such siphoning, and the atmospheric pressure upon liquid in the tank A will consequently force the same upwardly through 65 the entrance 18 into the stem 15 and downwardly through the discharge pipe C thus effecting the main siphonic effect.
- 70 Since the combined effects of the main siphon and auxiliary siphon G is to discharge a greater quantity of liquid than the supply of the same into the tank A, the level of liquid within the tank A will consequently fall, and notwithstanding the fall of such liquid the auxiliary siphon G and main siphon will continue to operate until the liquid has fallen below the entrance opening 75 80 85 90 formed or cast integral. All parts of the structure are preferably of brass or some non-corrodible metal.

From the foregoing, it can be seen that an automatic siphon has been provided, in which an automatic and intermittent discharge of liquid from a container can be effected; and one in which all parts are readily accessible due to the detachable assembly of the various parts.

Various changes in the shape, size, and arrangement of parts may be made to the form of the invention herein shown and described, without departing from the spirit 15 of the invention or the scope of the claims.

I claim:

1. An automatic siphon, comprising in combination a main siphon, a valve regulating entrance to said main siphon, an auxiliary siphon, and a tube cooperating intermediate said auxiliary siphon and regulating valve adapted to have a vacuum created therein upon operation of said auxiliary siphon for operating said valve.

2. In an automatic siphon, the combination with a tank adapted for containing liquids, of means for automatically flushing the tank at intervals, including a siphon, a valve for regulating entrance to said siphon, and siphonic controlled vacuum means for regulating said valve.

3. An automatic siphon comprising in combination an outlet pipe, an inlet pipe, valve means regulating communication of said outlet and inlet pipes, an auxiliary siphon tube, and a vacuum tube operated by said auxiliary siphon tube and adapted to control said valve means.

4. The combination with a tank adapted to continuously receive a supply of liquid, of automatic siphon means for flushing the tank at intervals including an auxiliary siphon tube adapted to carry off liquid from said tank in quantity less than the inflowing liquid, a main siphon greater in effective volume than said auxiliary siphon, valve means for regulating entrance of liquid into said main siphon, and vacuum means operated by operation of said auxiliary siphon means and adapted to regulate said valve whereby upon opening of said valve said main vacuum will draw liquid from said tank, said valve adapted to automatically close upon said liquid reaching a predetermined level.

5. An automatic siphon comprising in combination a main siphon outlet including an entrance passageway, a valve reciprocably mounted in said entrance passageway, an auxiliary siphon detachably mounted in said main siphon outlet for operation independent of said main siphon, and a tube

connecting said auxiliary siphon and entrance passageway, and adapted to have a vacuum created therein upon operation of 65 said auxiliary siphon for operation of said valve.

6. In an automatic siphon, the combination with a tank adapted to continuously receive a supply of liquid, of a outlet pipe 70 adjustably mounted in said tank, valve means controlling exit of said liquid through said pipe, an auxiliary siphon for discharging liquid from the tank being less in effective discharge than the quantity of 75 inflowing liquid, and a vacuum tube communicating between said auxiliary siphon and valve means, said auxiliary siphon adapted to be automatically operated upon the liquid level rising to submerge the same 80 for creating a vacuum in said vacuum tube for opening of said valve.

7. An automatic siphon comprising a main siphon, a valve for controlling flow of liquid through the main siphon, an auxiliary siphon, and means connecting the auxiliary siphon to the main siphon for controlling operation of the valve in the latter.

8. An automatic siphon adapted for intermittent discharge of continuously supplied liquids comprising a main siphon adapted for the discharge of liquids in greater quantity than they can be supplied, a valve for controlling flow of liquids 95 through the main siphon, an auxiliary siphon, and means connecting the auxiliary siphon to the main siphon for control of the valve with respect to the main siphon, said auxiliary siphon being adapted for discharge of a quantity of liquid less than that 100 quantity which is supplied.

9. An automatic siphon device comprising a main siphon including a discharge portion, an inlet portion, and a portion connecting the discharge portion intermediate the ends of the inlet portion, a valve slideable in the inlet portion of the main siphon, an auxiliary siphon of smaller capacity than the main siphon, and means connecting the auxiliary siphon with the upper end of the inlet portion of the main siphon, whereby upon operation of the auxiliary siphon a vacuum may be created in the upper end of the inlet portion of the main siphon for 115 operating the valve in the main siphon so that water may flow into the discharge portion of the main siphon.

10. An automatic siphon comprising a siphon structure, and vacuum controlled 120 valve means for regulating operation of said siphon.

RUSSELL J. ANDREWS.
